HUMIDIFIER

Samuel Neiburger, Chicago, Ill., assignor to Rudolph H. Guenther, Chicago, Ill.

Application February 25, 1932. Serial No. 595,123

4 Claims. (Cl. 237—78)

This invention relates to improvements in humidifiers, particularly adapted to be connected with a heating radiator in a room, for the purpose of providing moisture to the heated air, and one of the objects of the invention is to provide an improved pan or receptacle for receiving and holding water, and which pan is of a size and shape to be readily connected to the radiator by projecting the same into the radiator through one of the openings thereof and between the radiator coils.

A further object is to provide an improved pan or receptacle of this character having connected thereto, as an integral structure, a supply reservoir, which latter when the device is in position, will be located outside of the radiator coils where access may be readily had thereto, for the purpose of filling the same with water.

A further object is to provide in connection with the pan or receptacle a wick preferably in the form of a thick porous pad which projects for a considerable distance above the pan, the water being carried by capillary attraction to the exposed surfaces of the wick, and is evaporated by the heat of the radiator; the wick or pad being of a substantially rigid nature so that it will not wilt or fall down, but will remain erect and out of contact with the coils of the radiator.

To the attainment of these ends and the accomplishment of other new and useful objects as will appear, the invention consists in the features of novelty in substantially the construction, combination and arrangement of the several parts hereinafter more fully described and claimed and shown in the accompanying drawings illustrating this invention and in which

Figure 1 is a perspective view of a radiator having a portion thereof broken away and with a humidifier constructed in accordance with the principles of this invention, attached thereto.

Figure 2 is a detail perspective view of the humidifier with the wick or pad separated therefrom.

Figure 3 is a longitudinal, sectional view of the humidifier with the wick or pad in position.

Figure 4 is a detail top plan view of the reservoir end of the humidifier.

Figure 5 is a detail sectional view taken on line 5—5, Figure 3.

Figure 6 is a perspective view of another form of the invention with the wick adapted to be used in connection therewith and showing the wick separated from the humidifier.

Figure 7 is a detail top plan view of the reservoir end of the humidifier.

Figure 8 is a detail sectional view taken on line 8—8, Figure 10.

Figure 9 is a sectional view taken on line 9—9, Figure 7.

Figure 10 is a sectional view taken on line 10—10, Figure 7.

Referring more particularly to the drawings and in the form of the invention shown in Figure 1, the humidifier consists essentially of a body portion 15 constructed of any desired or suitable

material which is formed into a pan or receptacle

comparatively long with relation to its width and height, and 16 designates a reservoir which is formed integral with the body portion 15 and

communicates with the interior of the pan. This

reservoir 16 may be of any desired size and configuration and diameter, but is of a diameter

considerably greater than the width of the pan or receptacle.

The bottom 17 of the reservoir inclines downwardly from the outer portion

thereof toward the base of the pan or receptacle

15, so as to direct all of the water which may be

contained in the reservoir portion 16 into the

pan. The structure thus formed is produced

from a blank or single piece of sheet material

bent upon a medial line to form the bottom and

opposite side walls of the pan. The pan 15 may

be of any desired length so as to permit the de-

vice to be attached to a radiator by inserting

the pan portion thereof between the coils of the

radiator through the openings in the radiator,

the device being supported by the bottoms of the

openings by resting thereupon.

If desired a suitable wick or pad 18 constructed

of any suitable porous material may be em-

ployed and is of a size to fit within the pan por-

tion 15 and extend for a substantial distance

above the top thereof. The material from which

the pad or wick is constructed is rigid so as to

insure that the pad will stand uprightly and

will not wilt or fall over against the coils of

the radiator.

The bottom of the pad or wick is preferably

notched as at 19 so as to form extended areas

to facilitate in the absorption of the water in

the pan, and if desired the body of the wick or

pad may be provided with apertures 20 there-

through.

In use the wick may be placed within the pan

15 or may be omitted if desired. The device is

then connected to the radiator by passing the

pan portion through the openings in the radi-

ator, after which water or any other suitable

liquid may be supplied to the pan by pouring

the same into the reservoir portion 16 through

110

the open top thereof. By reason of the inclined bottom 17 of the reservoir 16 all of the water which is in the reservoir will be supplied to the pan.

5 In the form of the invention shown in Figures 6 to 10, the pan portion 21 is of substantially the same configuration as the form shown in Figures 1 to 3, and the reservoir 22 which is formed integrally therewith is also provided 10 with an inclined bottom 23. A portion of the walls of the pan or of the reservoir between the reservoir and the pan 21 are deflected outwardly as at 24 and then bent back upon themselves as at 25 to form opposed guideways which open 15 towards each other and which are arranged for any desired distance beyond the lateral sides of the pan portion 21.

In this form of the invention a pad or wick 26 suitably shaped and preferably provided with 20 a tapered lower portion 27 is inserted in the guides 25 so as to extend transversely across the opening between the pan and reservoir. By reason of the inclined or tapered bottom 23 of the reservoir 22, the lower extremity 28 of the pad or wick 26 will be spaced above the bottom of the reservoir as at 29 so as to form an opening 25 to permit the water from the reservoir to flow into the pan 21.

In this form of the invention the pad 26 being 30 of a porous material will cause the water to be drawn upwardly thereinto by capillary attraction so that the heat from the radiator contacting with the surfaces of the pad will cause the water to evaporate, thereby imparting humidity 35 to the atmosphere.

This form of the invention is adapted to be applied to the same radiator in the same manner as the form shown in Figures 1 to 3, that is by inserting the pan portion 27 between the coils 40 of the radiator through openings in the radiator.

With both of the forms of the invention, it will be manifest that the pan portions are of such a length with respect to the reservoirs that the weight of the water in the reservoir will 45 not cause the pans to become overbalanced and tip, but the pan portions will extend into the radiator a sufficient distance to prevent overbalancing or tipping of the device.

While the preferred forms of the invention 50 have been herein shown and described, it is to be understood that various changes may be made in the details of construction and in the combination and arrangement of the several parts, within the scope of the claims, without departing 55 from the spirit of this invention.

What is claimed as new is:—

1. A humidifier of the character described comprising a body portion shaped to form an open receptacle comparatively long with respect 60 to its width and height and adapted to be inserted between the coils of a radiator, an open

supply reservoir at one end of and communicating with the interior of the receptacle, a portion of the wall of said reservoir being shaped to form a wick receiving seat adjacent the junction of the receptacle and reservoir and of a greater width than the receptacle and extending transverse to the receptacle at the point of juncture of the receptacle and the reservoir. 80

2. A humidifier of the character described comprising a body portion shaped to form an open receptacle comparatively long with respect to its width and height and adapted to be inserted between the coils of a radiator, an open supply reservoir at one end of and communicating with the interior of the receptacle, a portion of the wall of said reservoir being shaped to form co-operating pad receiving seats adjacent the junction of the receptacle and reservoir and opening towards each other and disposed to hold a pad transverse to the width of the receptacle, the bottom of the reservoir inclining downwardly and tapering towards the bottom of the receptacle. 95

3. A humidifier of the character described comprising a body portion shaped to form an open receptacle comparatively long with respect to its width and height and adapted to be inserted between the coils of a radiator, an open supply reservoir at one end of and communicating with the interior of the receptacle, said reservoir being of a diameter considerably greater than the width of the receptacle, portions of the wall of the reservoir being shaped to form opposed guideways for receiving and holding an absorbent pad with its longitudinal axis intersecting the longitudinal axis of the said receptacle. 100

4. A humidifier of the character described formed from a single piece of sheet material and shaped to form a pan portion and a supply reservoir at one end and communicating therewith, the said pan portion being comparatively long with relation to its height and width and adapted to be inserted between the coils of a radiator through one of the openings in the radiator, the supply reservoir being exterior of but in proximity to the outer face of the radiator, the diameter of the reservoir in a direction transverse to the longitudinal diameter of the pan being considerably greater than the width of the pan, whereby a portion of the wall of the reservoir will form a stop to limit the insertion of the pan between the radiator coils, the bottom of the supply reservoir tapering downwardly to the bottom of the pan at the point of junction of the reservoir and the pan, said pan being of a length to overbalance the reservoir at all times for holding the device in position with respect to the radiator. 115 120 125 130 135
